UNITED STATES PATENT OFFICE.

THOMAS J. MAJCHRZAK, OF GRAND RAPIDS, MICHIGAN.

FLUID-FUEL BURNER.

Application filed February 29, 1924. Serial No. 695,877.

To all whom it may concern:

Be it known that I, THOMAS J. MAJCHRZAK, a citizen of the United States, residing at Grand Rapids, in the county of Kent and State of Michigan, have invented new and useful Improvements in Fluid-Fuel Burners, of which the following is a specification.

The present invention relates to fluid-fuel burners; and its object is to provide in such a burner means for forcing the flame in a horizontal direction by an air-draft, to thus heat a surrounding air-heating element; and further, to provide in such a burner improved specific parts and constructions.

This and any other objects hereinafter appearing are attained by, and the invention finds preferable embodiment in, the structure hereinafter particularly described in the body of this specification and illustrated by the accompanying drawings, in which:—

Figure 1 is a vertical sectional view of a furnace having a fluid-fuel burner applied thereto;

Figure 2 is a top plan view of the burner, its upper member being partially broken away;

Figure 3 is a side view of the same, shown partly in central vertical section taken on line 3—3 of Figure 2; and

Figure 4 is another side view of a portion of the same, partly sectioned on line 4—4 of Figure 2.

In the construction illustrated by the drawings, the furnace 1 having a casing 2 is equipped with an oil-burner which comprises a base member 3 suitably supported, as by the hollow cylinder 4 resting on the grate-bars 5 of the furnace, which (as in the form shown) may have been originally intended for burning solid fuel. This base member 3 has a vertically disposed air-draft passage 6 therethrough, registering with a like passage 7 through the cylindrical support 4. The burner comprises also an upper member 8 forming the upper wall of the upper portion of the air-draft passage 6 and having its under surface 9 inclined upwardly-outwardly as particularly shown in Figure 3. The burner further comprises a feeding pipe 10 for the oil, whose discharge vent 11 is located below the upper member 8 and adjacent the upper and outer end of the passage 6. Oppositely disposed open-top containers or shallow basins 12 are formed in the upper end of the base member 3 and are provided with drain pipes 13

extending upwardly thereinto to drain the oil accumulating above the level of their inner ends. The upper member 8 has a centrally disposed orifice 14 through which (and through the air-draft openings 6 and 7) the feeding pipe extends upwardly, then branching at 15, 15 and extending downwardly through holes 16, 16 in the upper member to their discharge vents. The base member 3 has oppositely disposed upwardly extending flanges 17, 18 between the basins 12 and provided with shallow air-draft depressions 19 through which any gas which may collect is expelled, by the draft, between the upper and lower members 8 and 3, and is consumed by the flames of the burning oil. These flanges have wing portions 20 at their ends, the discharge vents 11 of the branches 15 of the feeding pipe 75 being located between adjacent portions 20 of the two flanges.

It will be seen that the flames (indicated at 21) from the burning oil in the shallow basins 12 are driven outwardly in a horizontal direction by the air passing upwardly through the passage 6 and between the upper member 8 and the base member 3, and are thus driven against the air-heating element 22 forming the combustion chamber of the furnace, and thus thoroughly and quickly heats the same, so that the air surrounding the furnace is heated in like manner.

It will also be seen that the parts comprised in said burner are particularly well adapted to effect the general purposes of my invention. A pan or plate 23 may rest on the grate bars 5 and be covered with heat-insulating material 24, as ashes or the like, to confine the heat from passing downwardly between the grate bars.

The invention being intended to be pointed out in the claims, is not to be limited to or by details of construction of the particular embodiment thereof illustrated by the drawings or hereinbefore described.

I claim:

1. A burner having a vertically disposed air-draft passage therethrough with an upwardly-outwardly inclined upper portion, and having a fluid-fuel feeding pipe with a discharge vent below and adjacent the upper wall of the upper-outer end of said passage.

2. In a burner: a base member having a vertically disposed air-draft passage therethrough; an upper member having an up-

wardly outwardly inclined under surface and forming the upper wall of the upper portion of said passage; a fluid-fuel feeding pipe having a discharge vent below said 5 upper member and adjacent the upper-outer end of said passage.

3. In a burner: a base member having a vertically disposed air-draft passage therethrough and an open-top container for fluid-10 fuel in its upper end; an upper member having an upwardly-outwardly inclined under surface and forming the upper wall of the upper portion of said passage; a fluid-fuel feeding pipe having a discharge vent below 15 said upper member and adjacent the upper-outer end of said passage.

4. In a burner: a base member having a vertically disposed air-draft passage therethrough; an upper member having an orifice 20 therethrough and an upwardly-outwardly inclined under surface and forming the upper wall of the upper portion of said passage; a fluid-fuel feeding pipe extending up-

wardly through said passage and said orifice and having a discharge vent below said upper member and adjacent the upper-outer end of said passage. 25

5. In a burner: a base member having a vertically disposed air-draft passage therethrough and oppositely disposed upwardly 30 extending flanges provided with air-draft depressions; an upper member having an orifice therethrough and an upwardly-outwardly inclined under surface and forming the upper wall of the upper portion of said passage; a fluid-fuel feeding pipe extending upwardly through said passage and said orifice and having branches with discharge vents below said upper member and adjacent the upper-outer end of said passage and 35 respectively between said flanges. 40

In testimony whereof I have hereunto set my hand at Grand Rapids, Michigan, this 25th day of February, 1924.

THOMAS J. MAJCHRZAK.
